UNITED STATES PATENT OFFICE

LUITPOLD OFFENBACHER, OF FURTH, GERMANY, ASSIGNOR TO THE FIRM BAYERISCHE SPIEGELGLAS-FABRIKEN BECHMANN-KUPFER A.-G., OF FURTH, GERMANY

MANUFACTURE OF SILVERED GLASS

Application filed April 28, 1928, Serial No. 273,585, and in Germany August 11, 1925.

This invention relates to an apparatus for finishing silvered glass, which considerably simplifies and shortens the methods hitherto employed.

According to the present invention the following devices are positioned one behind the other along a conveying arrangement: a mechanical flushing device for the silvered glass which flushes the entire breadth and both sides of the glass simultaneously, a drying device for the flushed glass, which operates with hot air under pressure, a mechanical spraying device for applying the shellac to the dried glass, a second drying device for the coating of shellac, which also operates with hot air under pressure, a second mechanical spraying device for applying the covering varnish and finally a third drying device for the coating of covering varnish, also operating with hot air under pressure.

A constructional example of such an arrangement according to the present invention is illustrated, in which

Fig. 1 shows the first half of the apparatus in side elevation,

Fig. 2 the second half of the apparatus in side elevation,

Fig. 3 the apparatus in cross-section on line A—A of Fig. 1 and

Fig. 4 the apparatus in cross-section on line B—B of Fig. 1.

In a frame 2, 3 mounted on supports 1 there are journalled a plurality of rotatable rollers 4, 5 and two drums 6 as carriers for an endless conveyor belt 7. The rollers 4, 5 are covered with rubber rings 10 and at one end of each roller is mounted outside the frame 2 a small toothed wheel 8, over which an endless chain 9 runs. On the conveyor belt lies a web of thin paper 11 which travels with the belt and which unrolls from a drum 12 and winds up on a drum 13 (Fig. 2). By belt transmission gear 14 (Fig. 1) the conveyor belt 7, the paper drums 12, 13 and the groups of rollers 4, 5 are coupled to an electric motor 15.

Above and below the rollers 4 and transversely of the conveyor device a plurality of water pipes 16 having a series of perforations 50 is so arranged that, when the valve 17 of the

supply pipe 18 is opened, jets of water are directed towards each other between the rollers 4 (Fig. 3). Between the rollers 5 the nozzles 19 of a hot air supply 20 are directed from above and below towards one another. The conveyor belt 7 is bridged over at its front end by a stirrup 21 (Fig. 4), to which a rocking arm 22 supporting a spraying pistol 23 is suspended. From the spraying pistol 23 a flexible tube 24 leads to a container 25 in which there is liquid shellac under pressure.

Behind the stirrup 21 a second group of nozzles 26 of a hot air supply 27 is located above the conveyor band 7 and behind these nozzles 26 a second spraying device 28 with a spraying pistol 29 is provided, the flexible tube 30 of which leads to a container 31, in which is liquid covering varnish under pressure. This spraying device 28, 29 is followed by a further blast device and at the end of the conveyor device is a table 33 for receiving the finished article.

When the motor 15 is switched on the rollers 4, 5 rotate in the direction of the arrow *a* and the upper stretch of the conveyor belt 7 travels in the direction of the arrow *b*. The web of paper 11 resting on the conveyor belt travels in the same direction and at the same speed. The silvered and flushed pieces of glass are placed on the rollers 4 or on the rubber rings on the same and through the rotation of the rollers are conveyed along in the direction of the arrow *b*. When travelling between the pipes 16, the pieces of glass are thoroughly flushed on both sides first with ordinary water and then with distilled water, whereby the last traces of superfluous silvering fluid are removed. From the rollers 4 the pieces of glass slide on the rollers 5 between the nozzles 19, through which a strong blast of hot air is blown against them on either side. After passing between the nozzles 19 the pieces of glass arrive in a completely clean and dry state on the conveyor belt 7 and under the spraying device 23.

Thereupon the shellac is applied mechanically to the pieces of glass by means of a spraying device 23 in contradistinction to the methods hitherto employed, in which the shel-

lac is applied with a brush. The shellac is sprayed in a thin layer on the glass by means of the spraying pistol 23 by compressed air, the glass being at the same time conveyed 5 along by the conveyor belt. Behind the spraying device the pieces of glass travel under a second hot air blast device 26, which causes the shellac to dry immediately. Consequently the pieces of glass can have the covering varnish applied to them immediately 10 after the application of the shellac by means of the spraying device 29. Finally the pieces of glass pass under a third hot air blast device 32 by which the covering varnish is also dried. 15 At the receiving table 33 the finished pieces of glass are removed as they arrive and are taken away to be further dealt with.

As compared with the known methods, that described above has the advantage that within 20 in six minutes a piece of glass is silvered and covered with varnish, i. e. completely finished, without having to be touched by hand during the whole operation. In many cases it will be sufficient to provide the pieces of 25 glass with covering varnish only, after they have been silvered. In this case the container 25 is not filled with shellac but with covering varnish, the second spraying device 30 and the blast device 32 being put out of operation.

30 What I claim is:

1. An apparatus for finishing silvered glass, comprising in combination with a continuous conveying device, a mechanical flushing device capable of covering the whole 35 breadth and the two sides of the glass, a drying device using hot air under pressure for the flushed glass, a mechanical spraying device for applying shellac to the dried glass and a second drying device using hot air under pressure for drying the coating of shellac, as and for the purpose set forth.

2. An apparatus for finishing silvered glass, comprising in combination with a continuous conveying device, a mechanical flushing device capable of covering the whole 45 breadth and the two sides of the glass, a drying device using hot air under pressure for the flushed glass, a mechanical spraying device for applying shellac to the dried glass, a 50 second drying device using hot air under pressure for drying the coating of shellac, a second mechanical spraying device for applying the covering varnish and a third drying device using hot air under pressure for drying the covering varnish, as and for the purpose set forth.

In testimony whereof I have signed my name to this specification.

LUITPOLD OFFENBACHER.
